Primary Examiner — Barbara Fox*Assistant Examiner* — Messina L Smith(74) *Attorney, Agent, or Firm* — Rabin & Berdo, P.C.(57) **CLAIM**

The ornamental design for a vital sign transmitter, as shown and described.

DESCRIPTION

FIG. 1 is a perspective view of a vital sign transmitter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the vital sign transmitter shown in use.

The broken lines shown in the drawings illustrate portions of the vital sign transmitter and the environment that form no part of the claimed design.

1 Claim, 8 Drawing Sheets(56)
